UNITED STATES PATENT OFFICE.

WILLIAM F. MULLER, OF BROOKLYN, NEW YORK, ASSIGNOR TO PERFECT RE-FILLABLE FUSE, INC., OF BROOKLYN, NEW YORK, A CORPORATION OF NEW YORK.

REFILLABLE ELECTRIC FUSE.

1,341,662.

Specification of Letters Patent.

Patented June 1, 1920.

Application filed March 1, 1919. Serial No. 279,976.

To all whom it may concern:

Be it known that I, WILLIAM F. MULLER, a citizen of the United States of America, residing at Brooklyn, Kings county, State 5 of New York, have invented certain new and useful Improvements in Refillable Electric Fuses, of which the following is a full, clear, and exact description.

This invention relates to improvements in 10 cartridge-fuses, the object being to provide an inexpensive yet efficient refillable fuse of this type, or in other words, to provide a casing to which a new fuse-wire can readily be attached after the fuse has blown. One 15 of the main objects of my invention is to provide a novel combination of parts arranged for the ready detachment of a blown fuse and attachment of a new one in lieu thereof.

20 In the accompanying drawing, forming part of this specification,

Figure 1 is a longitudinal sectional view, partly in elevation, of a fuse embodying my improvement; and

25 Fig. 2 is an end view looking from the left in Fig. 1, the plug and fuse-wire being omitted, the plate only being shown.

My improved fuse consists of a casing-member 4 having metallic terminals 5 and 30 6 suitably secured to the casing, one at each end thereof, to engage the fuse-clips of a circuit element. The casing 4 will be made out of suitable non-conducting material. The terminal 5, at one end of the casing, is 35 provided with a partition 7 intermediate its ends having an opening 8 for the passage of one end of a fuse-wire 9. The terminal 6 is also provided with a partition 10 having a relatively large opening 11 through which 40 the other end of the fuse-wire is passed to engage a removable plate 12 having an opening 13. The ends of the fuse 9 will be passed through the openings 8 and 13 and turned over as indicated. The threaded 45 socket portion 14 of each terminal carries a threaded plug 15, to jam the fuse-wire against the partitions of the terminals to insure perfect contact. Each terminal 5 and 6 consists of a cylinder divided into two 50 socket portions, having threads, by a parti-

tion-wall, which serves to virtually close the ends of the casing to which the terminals are applied. The relatively large opening 11 in the partition 10 of the terminal 6 serves two purposes, *i. e.* that of facilitating 55 the threading of the fuse-wire and also to permit any portion of a blown fuse to drop out should such portion be contained within the casing. The portion referred to will drop out when the fuse is placed in a vertical position, provided terminal 6 is lowermost. A fuse wire can be placed within the casing, after plugs 15 and plate 12 have been removed, by passing said fuse through opening 11, in partition 10, of terminal 6, 60 and then through opening 8 in partition 7 and finally turned over, as shown. After plate 12 has been passed over the adjacent end of the fuse 9, the fuse will be cut off and turned over. After having performed 65 the above operations, the plugs 15 will be placed in the terminals and screwed down firmly.

Having described my invention, what I 70 claim is:—

In a fuse, a casing, a terminal at one end thereof having a threaded bore, a wall at the end of said bore and integral with said terminal having a relatively small opening 75 to receive one end of a fuse-wire, a terminal 80 at the opposite end of said casing having a threaded bore, a wall at the end of said bore integral with said terminal having a relatively large opening for the passage of the opposite end of a fuse-wire, a removable 85 plate adjacent the wall with the large opening having a relatively small opening, a fuse wire passing through said openings, and a threaded plug for each terminal arranged to force the ends of the 90 fuse-wire against the wall of one terminal and the removable plate in the other terminal.

Signed at New York city, N. Y., this 27th day of February, 1919.

WILLIAM F. MULLER.
